CLAIBORNE PIRTL, OF CLEVELAND, OHIO.

CABLE-DRUM MECHANISM.

No. 873,781.

Specification of Letters Patent.

Patented Dec. 17, 1907

Application filed March 6, 1907. Serial No. 380,815.

To all whom it may concern:

Be it known that J. CLAIBORNE PIRTL, a citizen of the United States of America, residing at Cleveland, in the county of Cuyahoga and State of Ohio, have invented or discovered new and useful Improvements in Cable-Drum Mechanisms, of which the following is a specification.

On hoisting mechanisms it is often advisable to have in addition to the hoisting cable, a second cable connected to the hoist hook, the grab bucket, the lifting magnet, the car, or other load, handled by the hoisting mechanism. Said second cable may be used for leading current to a lifting magnet, or to visible or audible signals or for energizing any electrical apparatus, which travels with the hoisting cable or is stationary and must receive current at a certain point or points or for certain periods in the travel of the hoist. Said second cable need not carry current and may be used to mechanically operate various devices situated on or near the hoist rope or suspended from it. Said cable as described above will be referred to herein as the auxiliary cable. It is evident that movement of the auxiliary cable must be synchronous with that of the hoist cable. At the present time it is common practice to operate the auxiliary cable from a drum, other than the hoist drum, through a positive connection to the hoist drum. This connection is usually made by sprocket wheels and chain or by gears driven from some shaft in the hoisting mechanism. Even where the auxiliary cable drum is driven from the main hoist drum, it has been found impossible in practice to get this connection accurate enough to cause the cables to move in synchronism, and to get approximate synchronism each auxiliary cable drum must be designed for the particular hoisting mechanism with which it is to operate. Even with careful design, it has been found that the lack of synchronism between the main and auxiliary cables subjects the auxiliary cable to strains that often part it or break the gearing between the main and auxiliary cable drums. To prevent this a large loop must be left in the auxiliary cable, which is always objectionable and often prohibitive.

The object of my invention is to provide a cable-drum mechanism, which is generally applicable without special design to all types of hoisting machines; which is independent of the machine with which it is to operate and

may be placed either on the machine or in any other convenient location, which will cause the auxiliary cable to move in absolute synchronism with the main or other power cable, thus avoiding any loop in the auxiliary cable; which will prevent any undue strains in the auxiliary cable or cable-drum mechanism; and which will keep an even tension in the auxiliary cable irrespective of the position or direction of motion of the machine with which it is operating.

Referring to the drawing accompanying this specification, Figure 1 is a side elevation illustrating one form of my invention; Fig. 2, a similar view illustrating a second form thereof; Fig. 3, a side elevation of a crane showing my invention applied to the trolley thereof; Fig. 4, a similar elevation showing a modification of Fig. 3; and Fig. 5, a longitudinal section of the drum E shown on Fig. 1.

Referring to Fig. 1, A is an electric motor, whose shaft carries the pinion B meshing with the gear-wheel B' on the shaft F of the cable-drum E. This drum has a deep groove 80 extending from its periphery toward its center or axis. The cable is wound in a flat spiral in said groove and contains a pair of electric conductors c c' whose inner ends are connected to the respective slip rings c c' carried in the hub of the drum. The slip-rings have sliding contact with the brushes d d', to which are connected the wires d², d².

One of the supply wires G, G' leading to the motor A contains the resistance G², which is permanently in series with the motor and of such a value as to allow only a safe current for the motor to flow even with the motor stalled, and to limit the torque to a predetermined value at all times, which value must be sufficient to rotate the drum E and reel in the cable when the load to which the cable is attached rises or moves so as to tend to slacken the cable, but its value may, of course, be greater, if desired, so as to aid in the movement of the load. The main duty of the motor is to reel up the cable when the movement of the load will permit it to rotate, and it may do additional work at the option of the constructor.

If the hoist be ascending, the motor will rotate and take up the auxiliary cable in synchronism with the main or power cable. If the hoist be descending, the motor being connected to be driven by current only in one direction, the auxiliary cable will drag the motor backward. Thus, in either direction

of motion, the auxiliary cable moves in perfect synchronism with the main or power cable and no loop is required or permitted. Since the resistance G^2 is proportioned so as 5 to allow only a definite current to flow, the torque of the motor A is approximately constant and consequently the tension in the auxiliary cable is approximately constant.

It will be observed that in Fig. 1 the cable 10 drum is in the form of a reel, the cable winding on itself, which is the preferable form when the auxiliary cable is in the vertical position.

Fig. 2 shows a cable drum E' in the form 15 of a horizontal cylinder, which is the preferable form where the auxiliary cable is in the horizontal position.

On Fig. 3, I have shown my invention applied to an electric traveling crane, the cable-drum E and its driving mechanism being 20 mounted upon the trolley T, movable along the bridge T'. The drum E is used to pay in and out the electric cable C, conveying current to the lifting magnet M, which is connected to the cable N leading to the hoisting drum O carried by the trolley T and driven by the motor P.

In Fig. 4, the cable-drum E' with its driving mechanism is located on the bridge T 25 while the cable C extends out horizontally from the drum and then down over the idle pulley R on the trolley to the magnet M, which is suspended as shown in Fig. 3. The cable-drum must, in Fig. 4, compensate for both the travel of the load and the travel of the trolley.

It is obvious that other forms of my inven-

tion besides those shown in Figs. 1 and 2 might be adopted and that many other applications thereof than those shown in Figs. 40 3 and 4 might be made. For example, I might use the cable-drum mechanism as a counter-balance, since the torque of the motor may be adjusted to take up more than the weight of the cable. 45

I claim—

1. A tension device for cables, embracing a drum, an electric motor having its rotatable member connected in driving relation to said drum, and a resistance permanently in circuit with said motor in such manner as to limit the torque of said motor. 50

2. In an automatic tension device for cables, the combination of a rotatable cable-winding device, an electric motor for driving said winding device in such manner as to take up the slack as it occurs on the cable, and means for limiting the torque of said motor to a constant maximum value. 55

3. In a hoisting device, the combination of 60 a lifting magnet carried by the said hoisting device, a cable for supplying electric current to said lifting magnet, a winding device for taking in and paying out said cable, an electric motor tending to drive said winding device in such a direction as to maintain a tension in said cable, and means for limiting the torque of said motor. 65

Signed at Cleveland, Ohio, this 1st day of March 1907.

CLAIRBORNE PIRTLE.
